Patented Sept. 9, 1975

236,728

DENTAL FLOSS HOLDER OR SIMILAR ARTICLE

Jerrold B. Harris, 45 W. Sommerlyn Road,
Colorado Springs, Colo. 80906

Filed July 12, 1974, Ser. No. 488,022

Term of patent 3½ years

Int. Cl. D24—99

U.S. Cl. D24—1 D

Fig. 1

Fig. 2

Fig. 3

Fig. 4

Fig. 5

Fig. 6

FIG. 1 is a side elevational view of a dental floss holder or similar article showing my new design;

FIG. 2 is a top plan view thereof;

FIG. 3 is a bottom view thereof;

FIG. 4 is an elevational view of the opposite side of the dental floss holder or similar article;

FIG. 5 is a front view thereof; and

FIG. 6 is a rear view thereof.

I claim:

The design for a dental floss holder or similar article, as shown and described.
